(57) **CLAIM**

The ornamental design for a snow brush, as shown and described.

DESCRIPTION

FIG. 1 is perspective view of the snow brush;
FIG. 2 is a first side view of the snow brush of FIG. 1;
FIG. 3 is a bottom view of the snow brush of FIG. 1;
FIG. 4 is a top view of the snow brush of FIG. 1;
FIG. 5 is a second side view of the snow brush of FIG. 1;
FIG. 6 is a back view of the snow brush of FIG. 1; and,
FIG. 7 is a front view of the snow brush of FIG. 1.
The broken line showing of portions of a shaft is included for the purpose of illustrating environmental structure and forms no part of the claimed design.

1 Claim, 4 Drawing Sheets---
